WISTER P. BOTT, OF HOMER, LOUISIANA

SCORE BOARD

Application filed November 22, 1928. Serial No. 321,217.

This invention has for its object the provision of a score or bulletin board more particularly designed for use at football games whereby the spectators may be informed at all times of the score of the game, the period of play, the time left in the playing period and the distance through which the team having the ball must carry it in order to retain possession. The invention 10 provides a compact apparatus whereby all the essential data at any stage of a game will be prominently displayed in such a manner that the spectators will comprehend the same at a glance. The invention is illustrated in 15 the accompanying drawings and consists in certain novel features which will be herein-after first fully described and then more particularly defined in the appended claims.

In the drawings:

- 20 Fig. 1 is an elevation of a bulletin or score board embodying the invention,
- Fig. 2 is a rear elevation with parts in section,
- Fig. 3 is a transverse section on the line 25 3—3 of Fig. 2,
- Fig. 4 is an enlarged detail perspective view of the clock-controlling member and a sign element which is operated in conjunction with said clock-controlling member,
- 30 Fig. 5 is an enlarged sectional elevation of the signal mechanism which announces the close of a period of play, and
- Fig. 6 is a detail section on the line 6—6 of Fig. 5.
- 35 In carrying out the invention, there is employed a board or stand 1 which is set in an upright position and secured in place by having its lower end embedded in the ground or otherwise braced as may be preferred and 40 as will be understood. At the top of this board on the face thereof presented to the playing field are spaces 2 and 3 marked by more or less ornamental frames 4 in which are legends designating the respective teams, 45 such as "Homer" and "Visitors", all of which is clearly shown in Fig. 1. Below the indications 2 and 3 are openings 5 and 6 respectively, and mounted on the back of the board in position to pass across said openings or 50 slots are disks 7 bearing numerals upon their

faces which are exposed to view through the respective openings, as will be understood upon reference to Fig. 1. Two disks are provided at each opening and they are mounted in any convenient manner on the back of the 55 board so that they may be readily rotated and the numerals displayed by the several disks will be exposed directly below the respective signs or indications 2 and 3 so that they will, respectively, announce the score of 60 the teams. Between the openings 5 and 6, the word "Playing" is painted or otherwise displayed upon the face of the board, as shown clearly in Fig. 4, and hinged to the face of the board immediately below said 65 word is a blind or sign plate 8 which normally is so disposed as to permit the word "Playing" to be read but is adapted to extend upwardly and be held over the word "Playing" and to then display the words "Time 70 out", the latter position of this blind or sign plate being shown in Fig. 1. The blind 8 has secured to one end an end of a rock shaft 9 which is mounted upon the front of the board 1 and is provided adjacent the side edge of 75 the board with a crank arm 10 extending through a vertical slot 11 in the board to pass to the rear of the board. A pitman or operating rod 12 is pivoted to the end of the crank arm 10 and constitutes means for rocking the 80 blind when necessary, as will be presently more particularly set forth.

Upon the front of the sign board 1 below the blind 8 is a frame 13, in the front side of which is a pane 14 of glass or other transparent 85 material which will serve to protect the time-indicating devices while permitting them to be easily read. Said time indicators include a dial 15 painted or otherwise inscribed upon the face of the board and encircling a field 90 having radial bars or strips 16 defined therein in a color contrasting with the field of the dial so that it will attract attention and may be easily read. The degrees of the dial 15 represent seconds and the second hand of the 95 clock mechanism is in the form of a disk having a plurality of radial bars or arms 17 of the same form and dimensions as the strips or bars 16 and of the same color so that the field of the dial will appear alternately as a

solid color and as a series of radial stripes or bars so that the movement may be easily noted and the attention of the spectators will be attracted. One of the bars or arms 17 is formed with a pointer 18 at its free end which, by its position upon the graduated dial 15, will serve to mark the number of seconds left in the incomplete minute of the remaining time in the current playing period. Around the circle of degrees 15 are numerals, indicated at 19, which read counter-clockwise from 1 to 15 and denote minutes of play. Football games are played in four periods of fifteen minutes each playing time, and the time indicator includes a minute hand 20 which travels over the dial clockwise and by pointing to any one of the numerals 19 indicates the number of minutes left for play in the current period of the game. At the start of the period the minute hand points to the numeral 15, as shown in Fig. 1, and during the play the hand will travel past the respective numerals successively and at any time will indicate the number of minutes of play left in the period. The minute hand 20 and the second indicator are driven by an ordinary clock work mechanism housed in a casing 21 on the back of the board, said clock work including an escapement 22 cooperating with a pendulum 23 in the usual manner. Extending across the back of the board above the housing 21 is a lever 24 pivoted at one end to the board and having its other end pivotally attached to the pitman or connecting rod 12, as shown at 25. Between its ends a brake tooth 26 is formed on the lower edge of this lever and projects through an opening 27 in the top of the housing 21 to bear upon the dog 28 of the clock escapement. When play is in progress and the parts are working normally, the lever is above and out of contact with the dog, but if the play should be stopped for any reason, the pitman 12 is manipulated to swing the lever 24 downward so that the brake tooth 26 will bear upon the dog 28 and hold it in contact with the escapement wheel of the clock work so that the movement of the clock work will be arrested and the time-indicating elements 17 and 20 will be held at rest. When the lever 24 is thus rocked downwardly to stop the clock, the crank 10 is also swung downwardly so that the shaft 9 will be rocked and the blind 8 swung up to the position shown in Fig. 1 and display the announcement "Time out".

It is intended that the position of the lever 24 be controlled from the side lines of the playing field and to that end suitable electrical devices are provided including a magnet 29 mounted on the back of the bulletin board 1 below the lever 24 and adjacent the free end thereof, the lever constituting an armature for the magnet. A suitable source of current will be provided and at proper intervals along the side line will be provided

circuit closers so that, when the play is stopped for any reason, the lineman may close a circuit to energize the magnet 29 and thereby actuate the lever 24 to stop the clock. When play is resumed, the magnet will be de-energized and the operation of the clock will then automatically start anew. In order, however, that the time indicator may be controlled in the event that the electric mechanism should be out of order, the pitman 12 is carried downwardly to a point adjacent the bottom of the score board and there pivoted to a hand lever 30 which is pivotally mounted upon the back of the board.

It is desirable that the close of a playing period be announced in a positive manner, and my present invention includes means for automatically accomplishing this result. The arbor of the minute hand 20 extends entirely through the housing 21 and at its rear extremity is equipped with a beveled pinion 31 and a cam disk 32. The cam 32 bears against a tooth 33 on the under side of a lever 34 which is pivoted at one end upon the housing 21 and at its other end is pivoted to the upper end of a trigger or rod 35 which depends to a point near the bottom of the board, the lower extremity of this trigger or rod being pointed, as shown at 36 for a purpose which will be presently stated. The lever 34 plays in a guide bracket 37 on the back of the housing 21 and it is held constantly to the cam 32 by a contractile spring 38 attached at one end to the housing and at its opposite end to the lever, as shown in Fig. 2. The pinion 31 meshes with a similar pinion 39 on the upper end of a shaft 40 which extends downwardly to a point below the lower end of the rod 35 and is equipped at its lower extremity with a pinion 41. Said pinion 41 meshes with a gear 42 on the lower end of a cartridge holder 43 which is rotatably mounted on a spindle 44 held in suitable brackets 45 secured upon the back of the board. The cartridge holder 43 is a cylindrical body fitting closely upon the spindle 44 but easily rotatable about the same and provided at equi-distant points with four passages 46 opening through its upper and lower ends and each adapted to receive a cartridge, indicated at 47, the flange of the cartridge resting on the upper end of the holder, as shown in Fig. 5, whereby the cartridge will be supported and may be presented to the trigger or firing rod 35. Upon referring to Figs. 5 and 6, it will be noted that four cartridges are provided, and it will be obvious that it is intended to fire one of the cartridges at the end of each playing period. The parts are so timed and proportioned that the cartridge holder will make one-fourth of a revolution in fifteen minutes so that at the end of a playing period a cartridge will be brought into position directly under the pointed end 36 of the trigger or firing rod. 125 130

Just as the cartridge is brought into position below and in alinement with the firing rod, the high part of the cam 32 passes from under the tooth 33 of the firing lever 34, whereupon the spring 38 and the weight of the lever will cooperate to cause the same to drop sharply and drive the firing rod through the cap of the cartridge to fire the same.

Below the frame 13 which encloses the time indicators, openings 48, 49 and 50 are formed through the score board and on the back of the board are mounted disks 51, 52 and 53 which are adapted to display numerals through the respective openings, it being noted that there are two cooperating disks 53. Below the openings 48, 49 and 50 are displayed in any approved manner words or abbreviations "Down", "Qtr." and "Yds. to Go", as shown at 54 in Fig. 1. These legends are obviously intended to be read in connection with the numerals displayed through the corresponding openings and to inform the spectators of the number of the "Down" which a team is attempting to make, the period of play and the distance through which the ball must be carried by the team having possession thereof. The several indicating disks are intended to be manually set as conditions of the game may change so that the status of the game will be announced to the spectators and an operator for setting these several disks will be stationed back of the board. The board may be provided with a sight opening 55 below the legends 54 whereby the operator may post himself as to the progress of the game, but this sight opening is not essential inasmuch as it will be found more feasible to transmit the information to the operator through telephonic connections extending along the side of the playing field. Mounted upon the back of the score board at the lower portion of the same are a series of hand dials or knobs 56, each of which is connected by a chain 57 with a corresponding dial 7, 51, 52 or 53. The several dials 56 have displayed hereon numerals corresponding to the numerals on the signal dial which is operated by the respective hand dial so that the operator may be informed as to the numeral which is displayed through the face of the board. In order, however, that the operator may correctly read the announcement even though he cannot see it, the hand dials controlling the cooperating signal dials 53 as well as the op dials 7 are arranged reversely with respect to the signal dials and the operating chains cross each other, as will be understood upon reference to Fig. 2. When the sight opening 55 is employed, the chain 57 which transmits motion to the signal dial 52 will be carried around an idler 58 so that it will not pass across the sight opening.

From the foregoing description, taken in connection with the accompanying draw-

ings, it will be seen that I have provided a very simple and compact bulletin board which will be very advantageous for displaying the scores of football games. The working parts are not so heavy as to prohibit ready transportation of the board if it be preferred not to install it as a permanent fixture but the proportions of the board are such that it may be installed as a permanent fixture without detracting from the appearance of a playing field and it will serve to advise spectators of the exact score and conditions of play without requiring them to depend upon announcements of referees or other officials and will avoid disputes as to lapsed time.

While the score board is particularly designed and adapted for use at football games, it will, of course, be understood that by slightly changing or rearranging the numerals on the dial of the clock said score board may be used with equally good results when playing basketball, Rugby, and other athletic games.

Having thus described the invention, I claim:

1. A score board provided with a dial on its face, clock work mounted on the board, a time indicator movable over the dial by the clock work, a rotatable cartridge holder mounted on the board, means controlled by the clock work for continuously rotating the cartridge holder, and means controlled by the clock work for firing a cartridge in the holder when the time indicator has traveled a predetermined distance over the dial.

2. A score board provided with a dial on its face, a clock work mounted on the board, a time indicator movable over the dial by the clock work, the clock work having an arbor projecting therefrom, a cam on said arbor, a pinion on the arbor, a shaft mounted on the board, a pinion at the upper end of said shaft meshing with the pinion on the clock arbor, a cartridge holder adjacent the lower end of said shaft and rotated thereby, a lever pivoted on the board above the arbor and resting on the cam, yieldable means for holding the lever to the cam, and a firing rod pivoted to and depending from the lever for firing a cartridge in the cartridge holder.

In testimony whereof I affix my signature.
WISTER P. BOTT.
